UNITED STATES PATENT OFFICE.

JOSEPH B. SAGAN, OF PITTSBURGH, PENNSYLVANIA.

CORN HUSKER AND SHELLER.

Application filed December 12, 1923. Serial No. 680,101.

This invention relates to a corn husker and sheller.

One object of the invention is to provide a machine which both husks and shells corn.

5. Another object of the invention is to provide a machine which comprises a plurality of husking and shelling elements arranged to operate rapidly in performing both of such functions.

10 A further object of the invention is to provide a machine, having the above noted advantages, which may be mounted on the body of a motor driven truck and operated by the engine thereof.

15 In the accompanying drawings Figure 1 is a plan view of the husking and shelling mechanism, and of the truck upon which it is mounted and by the engine of which it is operated; Figure 2 is a side elevation of the
20 husking and shelling mechanism and of the

husking and shelling mechanism and of the truck; Figure 3 is a rear elevation of the husking and shelling mechanism and of the truck; Figure 4 is a fragmentary elevation of the screening mechanism of the machine;

25 Figure 5 is a sectional detail view of one of the husking and shelling elements of the machine, taken on the line 5—5 Figure 6 and showing such element at the completion of its stroke; Figure 6 is a horizontal section on

30 its stroke; Figure 6 is a horizontal section on the line 6—6 Figure 5 looking downwardly; Figure 7 is a horizontal sectional view looking upwardly from the line 7—7 Figure 5, and showing the tripping means of such ele-

35. ment; and Figure 8 is a sectional detail view of the husking and shelling element, taken on the line 8—8 Figure 6 and showing the element ready to receive an ear of corn just prior to the commencement of its stroke.

In the accompanying drawings the reference numeral 1 designates generally the superstructure comprising the corn husking and shelling mechanism proper, which is shown as mounted on the body of a truck 2.

shown as mounted on the body of a truck 2. Extending transversely of such superstructure 1, and mounted on the upper portion thereof, are two rows of hoppers 3, which lead to the husking and shelling elements of the mechanism.

50 A belt conveyer 4, for carrying unhusked corn to the top of the structure, discharges between the rows of hoppers 3, so that two operators may work simultaneously in taking ears of corn from the conveyor and inserting the same in the hoppers 3.

55 Each husking and shelling element proper,

designated generally by the reference numeral 5, is carried by a push rod, or vertical piston 6, slideable in frame members 7 of the machine. Push rod 6 carries a yoke 8 to which a plurality of arms 9 are fastened adjacent their lower extremities by means of hinges 10 on a ring 11. The arms 9 are segmental in cross section to leave a substantially circular space between them when the husking element or head is in closed position at the end of its stroke, as shown in Figures 5 and 6 of the drawings. Disposed between the arms 9 is a disk 12 arranged to serve as a floor or platform for ears of corn delivered to the husking head. This disk 12 is supported from the roof 13 of superstructure 1 by means of rods 14 which permit rotation of the disk on a vertical axis, but which do not permit vertical movement thereof.

Supported in a stationary frame 15 are yokes 16 carrying rollers 17 which bear against cam surfaces 18 on each of the arms 9. The outer extremities of arms 16^a of the yokes 16 bear against flat springs 19 secured 80 to the frame 15.

Movement of the push rod 6 in an upward direction causes the cam surfaces 18 on the arms 9 to pass over the rollers 17, which at the completion of the upward stroke, as shown in Figure 8 of the drawings, bear against the lower portion of the arms 9 adjacent the hinges 10 thereon, thus tending to spread the arms. The disk 12 being brought in its horizontal position, by an action to be hereinafter explained, during upward movement of the push rod and head springs 10^a on the ring 11 act on the lower extremities of the arms 9 to produce a positive spreading of the same. These springs are held during action of the arms by guides 9^b which lie in grooves 9^c in the arms. 85 90 95

Secured in the disk 12 at one side of the pivotal axis 12^a thereof is a rod 20, which is fastened to a lever arm 21 pivoted at 22 in a hanger 23. A coiled spring 24 secured to the short arm 21^a of the lever serves normally to maintain the opposite end of the lever in lowered position, wherein it does not affect the disposition of the disk 12. This position of the parts is shown in Figure 8 of the drawings. Suspended from the short arm 21^a of the lever is a rod 25, which terminates in a hook 25^a extending through an orifice 8^a in the yoke 8 on the push rod 6. 110

This rod 25 is unaffected by movement of the push rod except when the latter approaches the limit of its downward stroke. In such general position of the parts, the 5 hook 25^a of the rod is engaged by the yoke 8 to depress the short end of the lever 21 against the resistance of spring 24 and elevate the opposite end of the rod to tilt the disk 12 into the position shown in Figure 5.

10 Arranged as a vertical continuation of push rod 6 is a vertical rod 26, which extends upwardly through the roof 13 of the superstructure. This vertical rod 26 carries rollers 27 arranged to bear against a cam plate 28 carried by the rods 29 of a horizontally movable slide member 30. This slide member 30 comprises a plate 31 arranged in one position of the slide to close the orifice 32 at the lower extremity of the hopper 3. A 15 coiled spring 33 is arranged to bear against the slide member 30 to resist the action of rollers 27 on cam plate 28. The action of rod 26 serves to force the closure plate 31 to one side to open orifice 32 during upward movement of the push rod 6 and husking and shelling head 5, while the force exerted by spring 33 during the downward movement of push rod 6 and husking head 5 causes the plate 31 to close the orifice 32.

20 Figure 3 of the drawings illustrates particularly the operation of the rear set of push rods 6, which are shown as four in number and for the sake of convenience are designated in this figure by the distinctive 25 reference numerals 6, 6^a, 6^b, and 6^c. Each of the push rods is connected with a crank shaft 34 by means of connecting rods 36. The arms 37 of crank shaft 34 are preferably so arranged that all of the push rods and husking 30 heads are not simultaneously in the same position. Thus, the push rod 6 is shown at the lower limit of its stroke, the push rod 6^c at the upper limit of its stroke, and the intermediate push rods 6^a and 6^b 35 in an intermediate position. The forward crank shaft 38 of the machine, as shown in Figure 2 of the drawings, is driven by means of a crossed belt 39 which passes over a pulley 40 on the crank shaft and a pulley 41 on a counter shaft 42. Counter shaft 42 is driven by means of a belt 43 which passes over a pulley 44 on the counter shaft and a pulley 45 on the drive shaft 46 of the truck. The rear crank shaft 34, shown in Figure 3 of the drawings, is driven by means of a belt 48, which passes over a pulley 49 on the forward 50 crankshaft 38 and over a pulley 50 on the rearward crankshaft.

55 The belt conveyor 4 for carrying the unhusked and unshelled ears of corn to the top of superstructure 1 is driven by means of a belt 51, which passes over a pulley 52 on a shaft 53 mounted in outboard bearings 54 and over a pulley 55 on the shaft 56 of the conveyor. Pulley 52 is driven by means

of a belt 57 passing over a pulley 58 on the countershaft 42 of the machine. Associated with the belt conveyor 4 is an endless belt or movable table 59, carried by rollers 60. The shaft 61 of one of such rollers is extended, and carries a pulley 62 connected by means of a belt 63 with a pulley 64 on the shaft 56 of the belt conveyor 4. This arrangement not only conducts the ears of corn to be husked and shelled to the top of superstructure 1 but also carries them along between the rows of hoppers 3 in convenient position for their removal and insertion in the hoppers.

In use of the machine, the ears of corn 80 taken from the belt 59 are placed in the hoppers 3. As the push rod 6 associated with each of the hoppers reaches the limit of its upward stroke, the closure plate 31 associated with such hopper is moved to one side 85 in the manner previously described to open the orifice 32 at the bottom of the hopper. In this position of the husking head 5, as illustrated in Figure 8 of the drawings, the arms 9 of the head are open, and the disk 90 12 is in position to prevent the ear of corn from falling through the head.

As the push rod 6 moves downwardly 95 springs 9^a in the arms 9 grip the husk of an ear of corn and support it in vertical position. The husk of the ear is thus drawn off, and the grains of corn worked from the cob, by the action of the arms 9 in closing in on the ear and being drawn downwardly along the same, it being understood that the ear 100 of corn itself is held from vertical movement by the disk 12 on which it rests, and from lateral movement by springs 9^a. The gripping action of the arms 9 on the ear of corn in the husking and shelling head is 105 accentuated by means of the teeth 9^a on the interior face of each of the arms.

It may be found that the husks of any lot 110 of corn being husked and shelled are sufficiently green and tough to prevent ready stripping of the husks from the butt of the ear. In such case the butt may be severed from the remainder of the ear by striking it against a knife edge prior to the introduction of the ear into one of the hoppers 3. 115 In these circumstances the stripping of the husk may be readily effected by the action of the arms 9, such action taking the place of several manual movements in the actual stripping of the husks.

As the push rod 6 and husking and shelling head 5 approach the limit of their downward stroke, the tilting of the disk 12 permits the grains of corn, together with the husks and cob to fall downwardly into a 125 hopper 65, which directs them to a coarse screen 66.

It should be noted that the resilient means in the husking and shelling heads for gripping the ears of corn permit each head to 130

grip undersize ears firmly, and prevent damage to the mechanism by the insertion of oversize ears.

Screen 66 is inclined transversely of the machine, and is associated with a similarly inclined screen 67 of somewhat finer mesh, these screens each being secured respectively to rods 68 and 69 which are mounted respectively in the opposite extremity of the 10 lever arms 71, both of which are centrally pivoted at 71^a.

The operating connections for the screens comprises a short crank shaft 72, which is mounted in the outboard bearings 73, and 15 which has thereon a pulley 74 connected by a belt 75 with a pulley 76 on a shaft 77, which is mounted in outboard bearings 78. Shaft 77 also carries a pulley 79, which is connected by means of a belt 80 with a pulley 20 81 on the countershaft 42.

The crankshaft 72 is connected with the lower arm of the pivoted lever 71, or rather to the rod 69 connected therewith, by means of connecting rods 82.

25 On the shaft 77 are fans 83, which serve to carry husks along the inclined surface of the coarse screen 66 to a discharge spout 67^a.

In the operation of these features of the mechanism, the inclined screens 66 and 67 30 are continuously agitated, to effect a thorough separation of the grains of corn from the husks and cobs which have also fallen onto the screens. The husks will be blown outwardly to the discharge spout 67^a by 35 means of the fans 83, while the cobs will roll along the inclined surface of the screens to the same outlet.

The grains of corn, thus separated from 40 the husks and cobs flow to an inclined shoot or hopper 84, from which they pass for collection to a discharge orifice 85. Such discharge orifice may desirably be provided, as is shown in Figure 4 of the drawings, with a closure plate 86 operated by a handle 87.

45 The above mechanism is capable of husking and shelling a great number of ears of corn in a very short space of time. It is self contained, inasmuch as it is operated by the power of the truck upon which the 50 husking and shelling mechanism is mounted. It can thus be moved from place to place throughout a large district of country during the corn harvesting season, thus making the machine extremely practical from a 55 commercial view point in spite of the necessarily great expense involved by the details of its structure.

As the device of the present invention is 60 susceptible of numerous modifications without departing from the spirit of the invention, the scope of the invention is to be restricted only by the illustrations contained in the appended claims.

What I claim is:

65 1. In a corn husker and sheller the com-

bination of a push rod, means for actuating said push rod in a straight line, a husking and shelling head comprising a plurality of hinged arms carried by said push rod, and stationary means arranged to act upon said 70 husking and shelling head during movement thereof to open and close said arms and to produce the husking and shelling action of said head.

2. In a corn husker and sheller the combination of a husking and shelling head comprising a plurality of hinged arms and mounted for movement in a straight line, means for producing such movement of said 75 husking and shelling head, and stationary 80 means arranged to act upon said husking and shelling head during movement thereof to open and close said arms and to produce the husking and shelling action of said head. 85

3. In a corn husker and sheller the combination of a husking and shelling head comprising a plurality of hinged arms having cam surfaces thereon, means for producing movement of said husking and shelling head 90 in a straight line, and rollers arranged to bear upon the cam surfaces on said arms to open and close said arms during movement of the head. 95

4. In a corn husker and sheller the combination of a husking and shelling head comprising a plurality of hinged arms having cam surfaces thereon, actuating means for moving said husking and shelling head in a straight line, stationary means arranged to 100 act upon said husking and shelling head during movement thereof to open and close said arms, means for supplying ears of corn to said husking and shelling head, and means operated by the actuating means of said 105 head for opening and closing communication between said supplying means and said husking and shelling head. 109

5. In a corn husker and sheller a husking and shelling head having hinged arms, actuating means for said head comprising means for producing rectilinear movement thereof and means for opening and closing said arms, means for supplying ears of corn to said husking and shelling head, and means 110 operated by said actuating means for opening and closing communication between said supplying means and said husking and shelling head. 115

6. In a corn husker and sheller a husking and shelling head having hinged arms, actuating means for said head comprising means for producing rectilinear movement thereof and for opening and closing said arms, a rotatably mounted bottom closure for said head, and means operated by the actuating means of said head for rotating said bottom closure. 120

7. In a corn husker and sheller a husking and shelling head having hinged arms, actu- 125

130

ating means for said head comprising means for producing rectilinear movement thereof and for opening and closing said arms, a rotatably mounted bottom closure for said head, means operated by the actuating means of said head for rotating said bottom closure, means for supplying ears of corn to said husking and shelling head, and means operated by said actuating means for opening and closing communication between said supplying means and said husking and shell-
10 ing head.

8. In a corn husker and sheller a husking and shelling head having hinged arms, actu-
15 ating means for said head comprising means

for producing rectilinear movement thereof and means for opening and closing said arms, means for supplying ears of corn to said husking and shelling head, means operated by said actuating means for opening 20 and closing communication between said supplying means and said husking and shelling head, and means for separating husks and cobs from grain shelled by said head comprising an inclined screen and 25 means for creating a current of air along said screen.

In witness whereof, I hereunto set my hand.

JOSEPH B. SAGAN.
